UNITED STATES PATENT OFFICE.

SVANTE WILHELM NILSSON, OF STOCKHOLM, SWEDEN.

MEANS FOR PRODUCING FLOORINGS OF CONCRETE OR THE LIKE.

1,176,921.

Specification of Letters Patent. Patented Mar. 28, 1916.

Application filed November 3, 1913. Serial No. 798,894.

To all whom it may concern:

Be it known that I, SVANTE WILHELM NILSSON, a subject of the King of Sweden, residing at Stockholm, in the Kingdom of Sweden, have invented new and useful Improvements in Means for Producing Floorings of Concrete or the like, of which the following is a specification, reference being had to the drawing accompanying and forming a part thereof.

This invention relates to means for producing floorings of concrete or the like consisting of beams and a plate cast in one piece therewith.

The object of the invention is to reduce the expenses of the necessary casting-mold and consequently the manufacturing cost of the flooring. The casting-mold consists of a framing of plates, or the like, rigidly connected to each other by suitable stays, which during the casting will act as form-pieces for the side-surfaces of the beams, while a network inserted between the plates constitutes a form-piece for the underside of the plate situated between two beams.

The accompanying drawings illustrate a suitable form of such an arrangement.

Figure 1 shows a framing in vertical section taken on line A—B in Fig. 2. Fig. 2 is a top plan view of the mold. Fig. 3 shows in vertical section the complete form for the casting of a concrete flooring, and Fig. 4 shows the ready flooring with the net-work brought down to lower edge of the beams.

The illustrated framing consists of two side-plates 1, connected at both ends by intersecting stays 2. The distance between the upper edges of the side-plates is somewhat shorter than the distance between their lower edges, thereby effecting a fair release. The cross-stays 2 are provided at their upper ends with depressions or recesses 3, wherein are placed bars 4 of rod-iron between which wires 5, bends or the like are stretched in such a way that a net-work is formed between the upper edges of the side-plates.

The preferable length of each framing is 1 yard, the width corresponding to the distance between the beams. The bars 4 can

be connected to the corresponding bars in the nearest situated framing by means of threaded sleeves 6 (Fig. 2).

The mounting of the complete framing for the casting of a concrete flooring is made as follows: Laid upon trestles 7 of suitable height are girders 8, and on said girders are placed planks 9 intended to serve as form-pieces for the lower sides of the beams, and consequently extending longitudinally in the direction of the beams being in preparation. Placed on said planks 9, in the manner indicated in Fig. 3, are rows of the aforesaid framings, being preferably secured by nails driven into the planks through holes 10 placed for this purpose in the lower edges of the plates 1. Further, at suitable distances apart not exceeding the length of each framing are secured to the planks wooden blocks 11, intended to be cast in the concrete-beams, for the below mentioned purpose. The net-work 5 of the framings is finally covered with asphalt-paper 12 or the like, bent down over the edges of the plates 1. The mold is now ready, and the beams 13 together with the adjoining plate 14 can be cast in usual manner, and if needed the beams may be reinforced by strengthening irons. When the flooring has hardened, the trestles 7, the girders 8, the planks 9 and the framings together with the net-work 5 are removed. Supporting irons 15 each provided at their ends with hooks are secured to the blocks 11, cast in the beams. The rods 4 and the net-work 5 stretched between said rods are placed in said hooks, and finally the nails or screws 16 supporting the irons 15 are completely driven home. The net-work 5 which is stretched accordingly between the lower edges of the beams 13 (Fig. 4) forms a framing to which can be secured immediately the dressing or some other bedding for instance reed webs. The removed framings 1 and 2 can of course be used for casting a well-nigh unlimited number of floorings, whereby the costs of the framing will soon be repaid. The asphalt-paper 12, however, remains on the net-work when being moved downward, and will act as an isolating member.

What I claim and desire to secure by Letters Patent, is:

The combination with a framing for producing floorings of concrete or the like of a mold consisting of side plates rigidly connected to each other by means of stays, said stays provided at their ends with recesses and rods placed in said recesses and ar-

ranged to support a net-work serving as bedding for the dressing, substantially as 10 and for the purpose set forth.

SVANTE WILHELM NILSSON.
